LINE INDICATOR OR COPYHOLDER FOR
TYPISTS

Rudolf Joksch, Vienna, Austria

Application April 16, 1934, Serial No. 720,845
In Germany April 28, 1933

5 Claims. (Cl. 120—34)

I have filed an application in Germany on the 28th April, 1933.

The present invention relates to line indicators and other guides or masks for facilitating reading of the kind used in connection with copy-holders for typewriters.

The object of the invention is to provide an improved line indicator, more particularly improved means for feeding the line indicator. One 10 characteristic feature of the improved device is the provision of a feeding member which at the commencement of a new line is operated by the pressure exerted by the typist upon the line spacing lever or equivalent device. The feeding member, on being operated, is first clamped to the 15 line indicator and is then moved to feed the indicator by a certain adjustable amount. When the force which first clamps and then feeds the member ceases, that is, when the member is released, a spring returns the member to its initial 20 position. A spring or other resilient member is interposed in the mechanism interposed between the line spacing lever and the feeding member so that during the last portion of the movement 25 of the spacing lever the feeding member can remain at rest and in contact with a stop limiting the movement of the feeding member. The employment of a feeding member which at the commencement of each feed is clamped to the indicator and is disengaged from the indicator at the 30 end of each operation, and the employment of a resilient member in the means transmitting movement to the feed member, have the advantage that the whole construction of the device becomes extremely simple and reliable in action and 35 that the device may be very easily and rapidly adjusted for a variable feed.

The accompanying drawing shows by way of example one construction embodying the features 40 of the invention.

Fig. 1 is a diagrammatic front view of the improved device, and

Fig. 2 shows a detail.

In the drawing 1 indicates a rod carrying at 45 its lower end a line indicator 2 or other guide or mask for facilitating reading. The rod 1 is operated, that is, fed downwardly relatively to the copy, by means of a lever 3, hereinafter referred to as the clamping lever. The clamping lever 3 is loosely mounted upon the rod 1 and the bore 50 of the lever 3 is so constructed that a slight pressure upon the end of the lever will cause the lever to jam upon the rod 1 and become immediately clamped thereto. Therefore, downward pressure 55 upon the end of the lever 3 will cause imme-

diate clamping of the lever 3 relatively to the rod 1 so that downward movement of the lever 3 will cause the rod 1 to be moved downwardly to feed the indicator 2. When the pressure upon the end of the lever 3 is released, a spring 4 acting upon the undersurface of the boss of the lever 3 will return the lever 3 to its initial position, the rod 1 remaining during this return movement of the lever 3 stationary. The rod 1 is guided in a stationary yoke-shaped member 21 (see Fig. 10 2), the upper shank 19 of the yoke 21 limiting the upward movement of the lever 3 and the lower shank 20 serving as the abutment of the spring 4. The yoke 21 is carried by a tube 9 which is fixed by means of two lateral arms or in any other 15 suitable way to a vertical member 10 of the frame of the copy-holder. A stop 16 mounted in an opening 14 of the lower shank 20 and accurately 20 adjustable by means of a scale 15 serves for limiting the downward movement of the lever 3 and thereby adjusting the amount of feed given to the indicator at each operation.

The clamping lever 3 has, in addition to the bore 7 through which the rod 1 passes, another bore 8 through which the tube 9 passes, the latter bore being sufficiently larger than the outer diameter of the tube 9 to avoid any possibility of jamming between the lever 3 and the tube 9. The tube 9 has two longitudinal slots 11 in which is guided a pin 12 which projects from the tube 30 at both ends and rests upon the upper surface of the lever 3. The pin is connected within the tube 9 to a member, preferably a cord 13, which passes over a guide roller 31 and is connected at its lower end to the upper arm 30 of a double 35 armed lever pivotally mounted at 25 in a stationary horizontal member 32 of the frame. The lower arm 24 of the lever is adapted to be acted upon by the line spacing lever 5. The lever 30, 24 is provided with a lateral arm 26 serving for 40 manual operation independently of the line spacing lever 5. The line indicator 2 is turnably mounted upon the rod 1 by means of a hub 17 in order to facilitate the insertion of the copy sheet 18 under the indicator. Moreover, owing 45 to this hinged connection, the indicator 2 has the tendency to rest under its own weight upon the copy sheet. In order to adapt the position of the rod 1 and the indicator 2 to the position of the copy sheet 18 or the thickness of the 50 shorthand book, the shanks 19, 20 of the yoke 21 are turnably mounted upon the tube 9 of the frame 10. The indicator 2 may be made of a transparent flexible material and is provided at its end with a metal weight 22 for the purpose 55

of obtaining good contact with the copy sheet 18. The rod 1 together with the indicator 2 may be manually moved in either direction by means of a handle 23 which is adapted to be folded. The 5 arm 24 of the lever 24, 30 is within the path of the line spacing lever 5 and is, on turning the platen 6 for a new line moved by the line spacer 5. This movement is transmitted by the upper arm 30, the cord 13 and pin 12 to the clamping lever 3 and by the latter to the rod 1 and the indicator 2. Feeding may be obtained independently of the 10 line spacer by pressure upon the arm 26. Instead of operating the clamping lever 3 by the spacing lever 5, the arm 24 may be arranged 15 to lie within the path of the carriage 27 so as to be actuated by the carriage. This arrangement is not, however, so advantageous as operation by the line spacing lever.

The frame 10 of the device is, in the construction 20 shown detachably fixed to the carriage 27 of the typewriter. The copy sheet 18 is supported by a plate 28 above the sheet 29 carried by the platen. This arrangement has the advantage that the point of the copy sheet 18 which 25 is actually being copied is always approximately vertically above the point at which the type strikes the paper 29. Consequently the typist has no difficulty in finding at any time the word 30 to be copied as this word lies always at the point of intersection of the indicator 2 with an imaginary line passing through the typing point. This arrangement therefore considerably facilitates to the typist the finding of the word or 35 point to be typed and the usual rather troublesome movement of the eyes between a copy sheet and the paper being typed upon is avoided.

It may be pointed out that the arm 30 is made 40 of resilient material, for instance, spring steel so that it can bend, under the action of the line spacing lever 5, after the lever 3 has reached its end position determined by the screw stop 16.

The operation is as follows:

On actuating the line spacing lever 5, the lower 45 arm 24 of the lever 30 is turned and the resilient member constituted by the spring arm 30 moves, by means of cord 13 guided over roller 31, the clamping lever 3. The clamping lever 3 is first tilted so as to clamp the rod 1 and is then moved 50 together with the rod 1 and the indicator 2 downwardly, this movement being limited by the screw stop 16. Further movement exerted upon the transmitting mechanism during the spacing 55 of the platen 6, is taken up by the spring arm 30, the latter being bent during the latter part of the movement of the spacing lever 5. After the completion of the spacing of the platen 6, the spacing lever returns to its initial position, and the clamping lever 3 is also returned to its 60 initial position by the spring 4. During this return movement the clamping lever slides loosely upon the rod 1, the rod 1 and the indicator 2 remaining stationary. If the operator wishes to feed the indicator 2 without operating the spacing lever 5, he depresses the arm 26 and thus 65 directly operates the cord 13 and the clamping lever 3. The frame members 10 which are directly fixed upon the carriage of the typewriter, are connected by a cross member 32 and a sheet iron plate 28 which serves as a support for the 70 copy sheet or shorthand book. Between the platen 6 and the cross member 32 sufficient free space is left for the passage of a sheet 29 carried upon the platen of the carriage 27. The cross member 32 may be provided with a member acting 75 as the lower support for the shorthand book.

A free space 33 is left between the lower edge of the support 28 and the cross member 32 to enable the lower portion of the copy sheet 18 to pass in a backward direction.

In the construction illustrated in the drawing, 5 an indicator is fed. It will, however, be understood that instead of feeding the indicator, the copy sheet may be moved by the employment of a movable support and a stationary indicator may be used.

I claim:

1. In a typewriter provided with a copy-holder, the sub-combination of: a rod carrying at its lower end an indicator; means for guiding said rod; a clamping lever loosely mounted upon said rod; a stop limiting the upward movement of said clamping lever upon said rod; an adjustable stop for limiting the downward movement of said clamping lever upon said rod in accordance with the required amount of feed; spring means tending 20 to move the clamping lever in the upward direction; and means operable by the spacing lever of the typewriter for moving said clamping lever in the downward direction upon said rod, said last mentioned means comprising a resilient member, substantially as and for the purpose described.

2. In a typewriter provided with a copy-holder, the sub-combination of: a rod carrying at its lower end an indicator; means for guiding said rod; a clamping lever loosely mounted upon said rod; a stop limiting the upward movement of said clamping lever upon said rod; an adjustable stop for limiting the downward movement of said clamping lever upon said rod in accordance with the required amount of feed; spring means tending 30 to move the clamping lever in the upward direction; and means operable by the spacing lever of the typewriter for moving said clamping lever in the downward direction upon said rod, said last mentioned means comprising a double-armed lever, the lower arm of which lies within the path of the spacing lever of the typewriter and the upper arm of which is in the form of a leaf spring, and a cord connected at its lower 40 end to the upper arm of the lever and connected at its upper end to the clamping lever, substantially as described.

3. In a typewriter provided with a copyholder, the sub-combination of: a line indicator; means for feeding said line indicator operable upon the completion of a line comprising in combination: a longitudinally movable rod carrying the indicator; a clamping lever slidably mounted upon said rod and adapted to be clamped thereto; an adjustable screw stop for limiting the movement of the indicator; a scale for facilitating the adjusting of said screw stop; and a resilient member interposed between a feed operating member and said clamping member, substantially as and for 50 the purpose described.

4. In a typewriter provided with a copy-holder, the sub-combination of: a platen carriage; a copy holder fixed to said carriage and comprising two rods; a cross member connecting said rods and adapted to serve as a support for a shorthand book; a plate slidably mounted upon said rod and serving as a support for a shorthand book or copy sheet, the lower edge of said plate being some distance above said cross member to enable the lower end of a copy sheet to be passed backward between the lower end of the plate and said cross member; a tube fixed to one of the rods; a yoke-shaped bracket turnably mounted upon said tube; a rod slidably mounted in perforations 70

of the ends of said yoke; a line indicator fixed to the lower end of said rod; a lever slidably mounted upon said rod and upon said tube and adapted to clamp said rod on being tilted; a spring interposed between the under surface of said lever and the lower shank of said rod; a screw stop in said yoke for limiting the movement of said lever; a pin guided in longitudinal slots of said tube and resting upon said lever; a cord attached to said pin and located inside said tube; a guide roller for guiding said cord; a double-armed lever pivotally mounted upon the copy-holder and attached at its upper end to the lower end of the cord, the lower end of the double-armed lever being within the path of the line spacing lever of the typewriter; an arm upon said double-armed lever for moving the lever independently of the line spacing lever; and a foldable handle at the lower end of the rod carrying the line indi-

cator for moving the rod independently of the feeding means in either direction, substantially as described.

5. In a typewriter provided with a copy-holder the sub-combination of: a line indicator; means for feeding said line indicator operable upon the completion of a line and comprising: a member adapted to be clamped to the indicator when moving in one direction and to be disengaged therefrom when moving in the opposite direction, 10 and a resilient member interposed between the line spacing lever of the typewriter and said member; means for varying the feed of the indicator; said line indicator being made of a flexible and transparent material and being provided with a 15 weight at its free end, and being pivotally mounted at its other end, substantially as and for the purpose described.
